[57] CLAIM

The ornamental design for a bottle or similar article, substantially as shown and described.

DESCRIPTION

FIG. 1 is a front elevational view of a bottle showing our new design, the back view being the same as the front;

FIG. 2 is a side elevational view thereof;

FIG. 3 is a cross sectional view taken along the lines
3—3 of FIG. 1;

FIG. 4 is a cross sectional view taken along the lines
4—4 of FIG. 1;

FIG. 5 is a bottom plan view thereof.
